ATTORNEY

UNITED STATES PATENT OFFICE.

JOHN J. DRURY, OF TROY, OHIO.

WASHING-MACHINE.

1,331,328.

Specification of Letters Patent.

Patented Feb. 17, 1920.

Application filed October 12, 1916. Serial No. 125,240.

To all whom it may concern:

Be it known that I, JOHN J. DRURY, a citizen of the United States, residing at Troy, in the county of Miami and State of Ohio, have invented certain new and useful Improvements in Washing-Machines, of which the following is a specification.

This invention relates to washing machines generally, and particularly to machines for washing bottles, jars, crocks, glasses, lamp chimneys and the like.

The invention aims primarily to provide a simplified and improved device for quickly and efficiently washing articles such as those mentioned above, and which shall prove easy and simple of operation. A further object of the invention is to provide a device of this character which is equipped with means for properly supporting the articles to be cleaned, and which automatically adjust themselves to the article upon application of the latter to the cleaner.

Still further objects reside in providing a device of this character and for these purposes which is of extremely simple and inexpensive construction, which is composed of but few readily assembled parts, all so constructed and arranged as to minimize the opportunity for wear or breakage, and which will prove thoroughly efficient in the attainment of the ends set forth.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:

Figure 1 is a side elevation, parts broken away, of a washing machine embodying the invention;

Fig. 2 is a sectional view taken upon line 2—2 of Fig. 1;

Fig. 3 is a similar view on line 3—3 of Fig. 1;

Fig. 4 is a sectional view taken on line 4—4 of Fig. 1 and on a slightly enlarged scale;

Fig. 5 is a plan view, parts broken away, of one of the bottle holding blocks; and

Fig. 6 is an edge view of the block shown in Fig. 5.

Referring now particularly to the drawings, 10 indicates a standard formed preferably of relatively thin narrow metal, and

to the upper portion of which is attached a laterally disposed frame 11. This frame may also be formed of strap metal, and the entire frame work is assembled by the use 60 of the bolts as shown to provide a rigid structure. A bracket member 12 is secured to the upper part of the frame work, and through the medium of which the frame work may be attached to a wall or other support; the lower portion of the standard 10 being also adapted to be secured to a support. The frame 11 includes spaced horizontally disposed bars 13, within which is journaled a shaft 14, the latter being held 65 against vertical sliding movement by collars 15. The upper end of this shaft has affixed thereto, a pinion 16, which enmeshes with a gear 17 affixed to a horizontally disposed shaft 18, the latter being mounted for rotation in the vertically disposed members of the frame 11. The shaft 18 may be rotated by means of the handle 19, but it must be understood that suitable power mechanism may, if desired, be belted or geared to the 70 shaft should it be desired to render the device power driven.

The lower end of the shaft 14 has detachably secured thereto a cleaner or buffer rod 20, the latter being connected to the said 85 shaft through the medium of a sleeve 21, held in position by a cotter pin 22. The rod 20 is threaded adjacent its ends as shown, to receive jam nuts 23, between which a wad retaining star or member 24 is 90 held. The threads upon the rod 20 extend inwardly from the ends of the latter a distance sufficient to permit of liberal adjustment of the cleaning wads, so that the device may be adapted to long or short bottles 95 or the like. The wads used as washers indicated at 50 in Fig. 7, may be formed of cloth, waste or the like, and it will also be understood that brushes may be secured to the cleaner rod if found practicable. It is 100 also apparent that the rods for insertion in the articles to be cleaned may be of various lengths, and may be provided throughout their extents with cleaning brushes, wads or the like.

Associated with the standard 10 for maintaining the bottles or other articles to be cleaned in proper position with relation to the rod 20, are blocks 25. These blocks may be formed of wood, composition or metal, but 110 in the latter instance the bottle engaging faces would preferably be lined with felt,

cloth or other soft and non-abrasive material. A guide strap 26 is secured over the rear face of each block and is provided with a central offset portion 27, constituting with the rear wall of the block a slot or opening 28 through which the standard 10 passes. The forward face of each block is concave as at 29 to conform to the contour of the side portion of a bottle. The lowermost 10 block is provided with forwardly and inwardly extending spring arms 30, for yieldably engaging around the body portion of a bottle. It is preferred that at least two holding blocks 25 be employed with the standard; the upper block being adapted to engage with the neck or reduced portion of the bottle or article, while the lower block engages the base portion of the article operated upon. As the blocks are slideable upon the standard 10, the upward movement of the bottle or other vessel or article in positioning the same over the lower end of the cleaner rod 20, causes the upper block 25 to be carried upwardly; the enlarged portion of the 15 receptacle engaging the concave portion 29 thereof and forcing the said block upwardly. After the article has been cleaned and removed from around the rod 20, the upper block 25 will gravitate to its lowermost position, and engage with the upper face of the lower block.

In operation, squeegees, wads or other cleaner elements 50 are secured between the jam nuts 23 upon the rod 20 and upon the 20 star or holder 24. These wads are adjusted upon the rod in position to engage with the bottom and neck portions of the bottle or article to be operated upon, so as to engage the entire inner surface of the articles. The 25 crank 19 is operated to deliver rapid rotary movement through the gearing 17-16 to the washer rod 20. The bottles are applied to the cleaner by moving the same upwardly beneath the lower end of the rod 20. The 30 shoulder portion of the bottle engages the upper block 25 and upward movement of the bottle carries the said block upwardly to hold the neck portion of the bottle at all times in proper spaced relation to the standard 20. The rapidly rotating wads engage the inner walls of the bottle and remove all matter adhering thereto.

With the use of a device of this character, it is obvious that the work of cleansing bottles and the like may be greatly expedited. 35 The blocks 25 may be changed in size and shape to accord with the articles operated upon.

While the present is a disclosure of the preferred embodiment of the invention, it 60 is to be understood that the invention is not limited thereto, but that various changes may be made in the construction, arrangement and proportion of parts, without departing from the scope of the invention, as 65 defined in the appended claims.

What is claimed is:—

1. In a device of the character described, the combination of a main frame, including a vertical standard, blocks having their rear edges bolted upon said standards, straps fixed upon said rear edges and having offset central portions embracing said standard, said blocks having notched forward receiving portions, one of said blocks being 75 grooved and having leaf springs fixed therein, the body portions of said springs being curved to cause the springs to extend toward each other, the remaining block being slideable upon said standard, whereby bottles of 80 various sizes may be received by said blocks and a cleaning means carried by said frame.

2. In a device of the character described, the combination of a main frame including a vertical standard having a substantially 85 looped over U-shaped upper end, a laterally disposed substantially U-shaped member having one side connected to the looped over end of said standard and the remaining side being connected to the standard, a substantially 90 L-shaped member having a depending foot and a horizontal foot, the horizontal foot being connected to the looped over portion of said standard and also being connected to the vertical portion of said standard, a driven shaft extending horizontally 95 of said frame and being connected to the vertical standard, and to the looped over portion thereof as well as to said L-shaped member, thus causing the shaft to be efficiently supported, a gear keyed upon said drive shaft, a vertically extending driven shaft connected to the laterally disposed portion and also extending through the L-shaped member, said driven shaft having a 100 pinion upon its upper end meshing with said gear, bottle retaining means carried by said standard, and a cleaning means connected to said driven shaft.

In testimony whereof I affix my signature 110 in presence of two witnesses.

JOHN J. DRURY.
